UNITED STATES PATENT OFFICE

BENJAMIN FISCHER, OF NEW YORK, N. Y.

DESIGN FOR A CHILD'S LEGGINGS

Application filed October 25, 1932. Serial No. 45,578. Term of patent 7 years.

To all whom it may concern:

Be it known that I, BENJAMIN FISCHER, a citizen of the United States, residing at New York, in the county of Bronx and State of New York, have invented a new, original, and ornamental Design for a Child's Leggings, of which the following is a specification, reference being had to the accompanying drawing, forming part thereof.

Figure 1 is a perspective view of a child's leggings, showing my new design, and

Figure 2 is a side elevational view thereof. The essential feature of my invention re-

sides in the formation of a bifurcated garment having a panel section in the front thereof connecting the upper portions of the legs by prominent stitching arranged in an ornamental outline, the upper meeting edges of the panel and the legs terminating in upwardly extending tabs for attaching shoulder straps thereto.

I claim:

The ornamental design for a child's leggings, as shown and described.

BENJAMIN FISCHER.
